(57) **CLAIM**

The ornamental design for an induction charger, as shown and described.

DESCRIPTION

FIG. 1 is a top, front, and right perspective view of an induction charger showing my new design;

FIG. 2 is a top, rear, and left perspective view thereof;

FIG. 3 is a top plan view thereof;

FIG. 4 is a left side elevation view thereof;

FIG. 5 is a right side elevation view thereof;

FIG. 6 is a bottom plan view thereof;

FIG. 7 is a front elevation view thereof; and,

FIG. 8 is a rear elevation view thereof.

The broken lines shown in the drawings are included for the purpose of illustrating environmental structure and form no part of the claimed design.
